UNITED STATES PATENT OFFICE.

GEORGES GASTON ROYER, OF PARIS, FRANCE.

THERMOSTAT.

Original application filed May 8, 1925, Serial No. 28,871, and in Canada May 12, 1925. Divided and this application filed February 6, 1926. Serial No. 86,440.

This invention relates to improvements in thermostats.

It is one of the primary objects of the invention to provide a durable, uniformly acting thermostat which will have great strength and at the same time be extremely sensitive.

It is a further object to provide a device of this character which may be simply constructed and which will not require further attention after it is once installed.

These and other objects will appear more fully from the following description when considered in connection with the drawings 15 in which:

The figure is a longitudinal sectional view of the present embodiment of the invention.

Referring to the details of the apparatus, the body part or casing of the thermostat is 20 shown in the present instance as formed of a tube or casing 5 forming an enclosed thermostatic chamber 4 which obviously may be formed of any desired shape or proportions. The casing 5 is closed at its upper 25 end by a stopper 6 provided with a milled head and maintained fluid-tight therein by soldering or other suitable means. The stopper 6 is preferably provided with a vent 7 obturated by a peg forced in after the tube 30 5 has been filled with an inert substance as described below. The numeral 9 indicates a plunger slidably mounted with respect to the casing 5 and provided with an inner head 8 against which one end of a coiled 35 compression spring 10 abuts. The plunger 9 is maintained in fluid-tight relation to the casing 5 by means of a stuffing box comprising a plastic packing material 11 which surrounds the plunger and is engaged with the 40 casing 5. A metallic cap or washer 12 preferably surrounds the plunger 9 and rests upon the packing material 11, the cap 12 being engaged by the outer end of the coiled spring 10. The spring thus acts in conjunction 45 with the pressure within the chamber 4 to maintain the packing material in tight sealed relation with the body of the plunger 9, the spring also exerting an inward tendency on the plunger 9 for further preventing 50 air being drawn into the thermostatic chamber during contraction of the thermostatic fluid. The plunger 9 is sealed with respect to the casing 5 through the packing material 11 only since the plunger body and head 55 8 move freely in the casing 5, being pref-

erably maintained out of contact with the side walls of the thermostatic chamber.

As illustrated, the chamber 4 within the casing 5 is entirely filled with an inert thermostatic fluid or semi-fluid material which 60 surrounds the plunger 9 and head 8. It is deemed preferable to employ a fluid, such for example as glycerine, for the thermostatic material because of the quality of this particular liquid of being substantially non- 65 compressible and having a relatively low point of fusion preventing the same from freezing at any usual temperatures. The packing material 11 preferably consists of a molded bi-conical washer formed of compressible anti-acid indiarubber. To prevent leakage of the glycerine or other thermostatic material through the joint formed between the plunger 9 and casing 5 a little 70 solid grease may be applied below the joint to obstruct all outlet. The outer end of the plunger 9 may have any desired form of operating element 13 for operating the device or devices to be controlled by the thermostat.

It will be seen that according to the construction disclosed, when there is an increase of temperature and a consequent expansion of the fluid in the chamber 4, a pressure is developed within the casing 5 and the plunger 9 is pushed outwardly from the casing 5, since the plunger is the only displaceable element through which the pressure in the chamber 4 may be relieved. Likewise upon a decrease in the temperature 90 of the thermostat with a resultant contraction of the volume of the thermostatic material or glycerine in the chamber 4, the plunger is drawn inwardly into the chamber of the thermostat in an obvious manner. The spring 10 compresses the packing material 11 so as to maintain a tight seal between the plunger 9 and casing 5, the spring further assisting in drawing the plunger 95 into the chamber 4 and preventing air from being drawn into this chamber when a contraction of the thermostatic material occurs.

It is to be understood that the thermostat may be made of different form and proportions than those shown in the drawing and may be used in any desired location for controlling or operating any preferred type of mechanism. One such use is disclosed in my United States application for patent, Serial No. 28,871, of which the present appli- 105

110

cation is a division. It is also to be understood that the thermostatic substance within the chamber 4 may be changed without departing from my invention as different fluids or liquids or even powder will produce useful results although I prefer the use of the liquid specified, and further that the scope of the invention is to be ascertained from the appended claims.

10 I claim as my invention:

1. A thermostat comprising a fluid container, a pressure responsive rod extending through the wall of said container, a packing ring surrounding said rod adjacent said wall and means disposed on said rod for compressing said packing ring in proportion to the increase in pressure developed in said container.

2. A thermostat comprising a fluid container, a rod extending through the wall of said container, a packing ring surrounding said rod adjacent said wall, a head on the extremity of said rod and means interposed between said packing member and said head for opposing the movement of said rod by an increase in pressure in said container and for compressing said packing ring upon movement of said rod.

3. A thermostat comprising a fluid container, a rod extending through the wall of said container, a packing ring surrounding said rod adjacent said wall, a head on the

extremity of said rod and means interposed between said packing member and said head disposed on said rod for opposing the movement of said rod by an increase in pressure in said container and for compressing said packing ring upon movement of said rod. 35

4. A thermostat comprising a fluid container, a rod extending through the wall of 40 said container, a packing ring surrounding said rod adjacent said wall, a head on the extremity of said rod and a spring interposed between said packing member and said head disposed on said rod for opposing 45 the movement of said rod by an increase in pressure in said container and for compressing said packing ring upon movement of said rod.

5. A thermostat comprising a tubular 50 fluid container, means for hermetically sealing one end of said container, a movable plunger extending through the other end of said container, a packing ring surrounding said plunger at the joint where it passes 55 through the wall of said container and means for forcing said packing ring against the end of said container as said plunger is displaced by the pressure developed in said container. 60

In testimony whereof I have affixed my signature.

GEORGES GASTON ROYER.
